DESIGN FOR A WASTEBASKET OR SIMILAR RECEPTACLE

Martha H. Connor, Baltimore, Md., assignor to Owens-Illinois Can Company, Wilmington, Del., a corporation of Delaware

Application January 21, 1937, Serial No. 67,168

Term of patent 7 years

To all whom it may concern:

Be it known that I, Martha H. Connor, a citizen of the United States, residing at Baltimore, in the State of Maryland, have invented a new, original, and ornamental Design for a Wastebasket or Similar Receptacle, of which the following is a specification, reference being had to the accompanying drawing, forming a part thereof.

The drawing is a perspective view of a wastebasket or similar receptacle showing my new design.

The opposite side of the article is plain to the extent that the ship illustration is not repeated.

I claim:

The ornamental design for a wastebasket or similar receptacle, substantially as shown and described.

MARTHA H. CONNOR.
